PRODUCTION OF EFFECTS IN FILMS,
SHEETS, AND SIMILAR MATERIALSBrian Edward Merriman Miller, London, England,
assignor to Celanese Corporation of America, a
corporation of DelawareNo Drawing. Application November 10, 1937, Se-
rial No. 173,849. In Great Britain September
15, 1937

11 Claims. (Cl. 41—33)

This invention relates to improvements in or relating to effect materials, and particularly to artificial films, sheets and similar materials exhibiting mother-of-pearl or other effects.

5 This application is a continuation in part of my application S. No. 83,328 filed June 3rd, 1936.

It has been discovered that materials exhibiting excellent ornamental effects may be obtained by causing the pile side of a pile fabric to adhere 10 to a translucent or transparent artificial film or similar material and thereafter separating the pile fabric from the film.

15 The term "film" used in the present specification is to be understood to include sheets, foils and similar materials, and the expression "trans-
parent films" is to be understood to include trans-
lucent films.

20 The degree of adhesion effected in accordance with this invention may vary widely. It may be only a light adhesion so that on stripping the pile fabric from the film separation is effected without leaving pile fibres adherent to the film so that the film merely carries the "pattern" of 25 the pile fabric impressed on it. Alternatively, the adhesion may be relatively strong so that on stripping the pile fabric from the film, pile fibres remain firmly adhered to the film, and in this case a more pronounced effect is obtained which is particularly valuable for many purposes.

30 The transparent film, which may be colorless or colored and may be embossed, may have a basis of regenerated cellulose or nitrocellulose or a non-cellulosic transparent substance, but materials having a basis of an organic derivative of cellulose, e. g. cellulose propionate, cellulose butyrate, cellulose nitro-acetate, methyl cellulose, 35 ethyl cellulose, benzyl cellulose, and particularly cellulose acetate, have been found to be specially valuable. Such materials, especially if they have 40 a high content of substituent groups, e. g. in the case of cellulose acetate corresponding to an acetyl content of 56—58% or more, are relatively moisture-resistant, which is of considerable value for certain purposes. However, films of other 45 substances may be employed, e. g. films having a basis of a polymerized vinyl acetate, a polymerized acrylic ester or ether or other synthetic resin.

50 The pile fabric employed may be made of any suitable material, e. g. cellulose acetate or other cellulose derivative, regenerated cellulose, cotton or natural silk. The pile and the base of the fabric may both be of the same substance or they may be different, e. g. the pile may be made of 55 cellulose acetate yarn and the base of the fabric

of cotton or linen yarn. Where it is desired to effect relatively strong adhesion between the pile fabric and the film it is preferable that the pile of the fabric should be made of the same substance or a similar substance to the material of the film. Thus there may be adhered to a film having a basis of an organic derivative of cellulose a pile fabric which has a pile of an organic derivative of cellulose. Where, on the other hand, it is desired to effect only light adhesion, the pile 10 of the fabric is preferably made of a different material from the material of the film, e. g. a cellulose derivative film may be caused to adhere to a pile fabric in which the pile is made of regenerated cellulose, cotton, natural silk or other 15 non-thermoplastic material.

Various effects may be obtained by employing pile fabrics in which the pile is dyed in one or more colors or is of uneven lustre due, for example, to the presence of cellulose acetate yarns 20 and regenerated cellulose yarns, or of lustrous and delustrated cellulose acetate yarns. Or, again, a pile fabric may be employed in which the pile is of uneven thickness, e. g. a locally carbonized pile fabric. Of particular value according to this 25 invention are pile fabrics in which the pile lies in different directions in different areas as, for example, crushed pile fabrics in which the pile yarns are laid in different directions in a more or less haphazard manner. Such fabrics may be 30 produced, for example, by pressing cellulose acetate pile fabrics with suitable rollers in the presence of steam. By the use of crushed pile fabrics beautiful ornamental effects resembling mother-of-pearl may be obtained. 35

It is not necessary, however, that the pile fabric should be a patterned fabric. Very good results can be obtained by the use of a plain pile fabric of uniform character, the pressing operation necessary to effect adhesion to the film itself 40 causing the lay of the pile to be deformed in a haphazard manner.

Adhesion between the pile fabric and the transparent film may be effected in any suitable manner. When the material of the film and/or the 45 material of the pile of the pile fabric are thermoplastic, e. g. in the case of a cellulose acetate film and a pile fabric having a pile of cellulose acetate yarns, the necessary degree of adhesion may be effected by means of heat and pressure, 50 for example, by placing the film on the pile surface of the fabric and pressing the film and the fabric together in a heated press or passing them between heated rollers. Or, again, the film and/or the pile may be moistened with a suit- 55

able softening agent and the film and pile fabric then pressed together with or without the use of heat.

- 5 Suitable softening agents for cellulose acetate materials are, for example, acetone, methylene ethylene ether, ethyl lactate, glycol monoacetate, methyl glycol monoacetate, mono-, di- and tri-acetins, diacetone alcohol and dioxane. Preferably a mixture containing a volatile solvent and 10 a relatively low boiling solvent is employed, e. g. a mixture of acetone and diacetone alcohol. The softening media may contain, if desired, a small proportion, e. g. 2-4%, of a cellulose derivative as, for example, cellulose acetate.
- 15 Instead of relying solely on the use of heat or an organic or inorganic softening agent to facilitate the adhesion, an adhesive substance may be employed.

20 After the adhesion has been effected the fabric is stripped from the film and the film may be brushed or rubbed down to remove any loose pile fibres which are not firmly adhered to it.

25 The products obtained according to the invention are very suitable for use, for example, for lamp shades and for the decoration of drums and other musical instruments. Materials where-in the film has a basis of cellulose acetate or other relatively water-resisting substance are also very suitable for use where resistance to washing or 30 to humid conditions is desirable, as, for example, for table tops and as wall decorations in bathrooms.

Having described my invention, what I desire to secure by Letters Patent is:

- 35 1. Process for the production of mother-of-pearl effects on transparent artificial films, which comprises causing the pile side of a crushed pile fabric to adhere to the film under pressure and thereafter stripping the pile fabric from the film.
- 40 2. Process for the production of mother-of-pearl effects on transparent artificial films, which comprises causing the pile side of a crushed pile fabric to adhere to the softened surface of a film under pressure and thereafter stripping the pile fabric from the film.
- 45 3. Process for the production of mother-of-pearl effects on transparent artificial films, which comprises causing the pile side of a crushed pile fabric to adhere to the film under pressure, and thereafter stripping the pile fabric from the film, the degree of adhesion effected being so light that on stripping the pile fabric from the film substantially no pile fibres remain firmly adhered to the film.
- 50 4. Process for the production of mother-of-pearl effects on transparent artificial films, which comprises causing to adhere to the film the pile

5 side of a crushed pile fabric, and thereafter stripping the pile fabric from the film, the degree of adhesion effected being such that on stripping the pile fabric from the film pile fibres remain firmly adhered to the film.

5 5. Process for the production of mother-of-pearl effects on transparent artificial films having a basis of cellulose derivatives, which comprises causing to adhere to the film the pile side of a crushed pile fabric, and thereafter stripping the pile fabric from the film, the degree of adhesion effected being such that on stripping the pile fabric from the film pile fibres remain firmly adhered to the film.

10 6. Process for the production of mother-of-pearl effects on transparent artificial films having a basis of cellulose derivatives, which comprises softening the surface of the film by treatment with an organic softening agent, causing the pile side of a crushed pile fabric to adhere 20 to the softened surface, and thereafter stripping the pile fabric from the film, the degree of adhesion effected being such that on stripping the pile fabric from the film pile fibres remain firmly adhered to the film.

15 7. Process for the production of mother-of-pearl effects on transparent artificial films having a basis of cellulose derivatives, which comprises pressing the pile side of a crushed pile fabric on to the surface of the film under the action 20 of heat so as to cause the pile fibres and the film to adhere together, and thereafter stripping the pile fabric from the film, the degree of adhesion effected being such that on stripping the pile fabric from the film pile fibres remain firmly 35 adhered to the film.

25 8. Process for the production of mother-of-pearl effects on cellulose acetate film, which comprises causing to adhere to the film the pile side of a crushed pile fabric in which the pile has a 40 basis of cellulose acetate, and thereafter stripping the pile fabric from the film, the degree of adhesion effected being such that on stripping the pile fabric from the film pile fibres remain firmly adhered to the film.

35 9. Transparent artificial films having pile fibres lying in different directions firmly adhered thereto, and presenting a mother-of-pearl effect.

40 10. Cellulose derivative films having pile fibres lying in different directions firmly adhered thereto, and presenting a mother-of-pearl effect.

45 11. Cellulose acetate films having cellulose acetate pile fibres lying in different directions firmly adhered thereto, and presenting a mother-of-pearl effect.

55 BRIAN EDWARD MERRIMAN MILLER.
